GAME TABLE HAVING A BUILT-IN ELECTRONIC DISPLAY

Harold R. Miller, Phoenix, Ariz., assignor to Western
Woodcraft Co., Inc., Phoenix, Ariz.

Filed June 13, 1974, Ser. No. 478,882

Term of patent 14 years

Int. Cl. D21—01
U.S. Cl. D34—5 J

fig. 1

fig. 2

fig. 4

fig. 3

FIG. 1 is a perspective view of a game table having a built-in electronic display showing my new design;

FIG. 2 is a rear side elevational view thereof;

FIG. 3 is a left side elevational view thereof; and

FIG. 4 is a bottom view thereof.

I claim:

The ornamental design for a game table having a built-in electronic display, as shown and described.
